UNITED STATES PATENT OFFICE.

FREDERICK A. STEVENS, OF PROVIDENCE, RHODE ISLAND.

DESIGN FOR AN EYEGLASS-GUARD.

43,913.

Specification for Design.

Patented Apr. 22, 1913.

Application filed November 22, 1912. Serial No. 733,003. Term of patent 7 years.

To all whom it may concern:

Be it known that I, FREDERICK A. STEVENS, a citizen of the United States, residing at Providence, in the county of Providence and State of Rhode Island, have invented a new, original, and ornamental Design for an Eyeglass-Guard, of which the following is a specification, reference being had to the accompanying drawing, forming part thereof.

The figure represents the guard in side view.

I claim:

The ornamental design for an eyeglass guard, as shown.

FREDERICK A. STEVENS.

Witnesses:

H. B. BURKE,
F. A. MACDONALD.
